[57] CLAIM

The ornamental design for a support for a frame of an outdoor play device or the like, as shown and described.

DESCRIPTION

FIG. 1 is a perspective view of a support for a frame of an outdoor play device or the like embodying my new design;

FIG. 2 is a rear elevational view thereof;

FIG. 3 is a right side elevational view thereof, the left side being a mirror image;

FIG. 4 is a top plan view thereof;

FIG. 5 is a bottom plan view thereof;

FIG. 6 is a front elevational view thereof;

FIG. 7 is a perspective view of a second embodiment of the design of FIG. 1, the only difference being the configuration of the lower edge;

FIG. 8 is a front elevational view of FIG. 7;

FIG. 9 is a rear elevational view of FIG. 7;

FIG. 10 is a perspective view of a third embodiment of the design of FIG. 1, the only difference being the extension of the horizontal element rearwardly;

FIG. 11 is a top plan view of FIG. 10;

FIG. 12 is a bottom plan view of FIG. 10;

FIG. 13 is a right side elevational view of FIG. 12, the left being a mirror image.
